LUTHER W. WAKEHAM, OF OAKLAND, CALIFORNIA

DISPENSING DEVICE

Application filed June 3, 1929. Serial No. 368,159.

The invention forming the subject matter of this application relates to dispensing devices, and more particularly to a shaving brush for dispensing shaving cream.

5 An object of the invention is to provide a brush having a hollow handle for receiving a shaving cream in which said handle is provided with means for discharging said cream into the bristles of said brush through 10 an opening formed in one end of said handle, and wherein said means operates a valve disposed in said opening for controlling the flow of cream from said brush handle.

15 A further object is to provide a brush having a hollow handle for receiving a shaving cream in which a piston is provided for discharging said cream into the bristles of said brush, through an opening in one end of said handle, and wherein a screw threaded 20 rod secured at one end to a removable cap rotatably mounted on said handle, reciprocates said piston in said handle, the arrangement being such that a valve disposed in said opening is connected to the other 25 end of said rod and is opened and closed in succession by the rotation of said rod.

Another object of this invention is to provide a device of the character set forth which is highly useful and simple in construction. Convenience of arrangement, lightness and comparative inexpensive of manufacture are further objects which have been borne in mind in the production and development of the invention.

35 With the foregoing and other objects in view which will be made manifest in the following detailed description and specifically pointed out in the appended claims, reference is had to the accompanying drawings 40 for an illustrative embodiment of the invention, wherein:

Fig. 1 is a side elevation of the device forming the invention;

Fig. 2 is a longitudinal sectional view 45 taken on the line 2—2 of Fig. 1;

Fig. 3 is a transverse sectional view taken on the line 3—3 of Fig. 2; and

Fig. 4 is a transverse sectional view taken on the line 4—4 of Fig. 2.

50 Referring to the accompanying drawings

wherein similar reference characters designate similar parts throughout, the various figures described above adequately illustrate my invention, and the following detailed description is commensurate with the above 55 mentioned drawings in enabling an artisan to construct and assemble the constituent parts of the same.

The device involves in the general organization a shaving brush designated as an 60 entirely by the reference numeral 5. Said brush comprises a cylindrical handle or casting 6 having a central bore 7 extending therethrough in which said bore is formed with two diametrically opposed longitudinal guide grooves 8. One end of the handle 6 is internally threaded, as at 9, for threaded engagement with an externally threaded head 11, which head is provided with an annular flange 12 at the outer end thereof for 65 abutment with the end of said handle. Numeral 13 indicates a plurality of bristles which are set in the outer end of the head 11 and extend outwardly therefrom forming 70 a brush.

Mounted in a central bore 14 which extends through the head 11 is a tubular sleeve 16 having an annular outward flange 17 at the open inner end thereof, which flange engages the surface of the inner end of the 80 head 11 and is secured thereto by means of suitable tacks or small screws. The outer end of the sleeve 16 is closed as at 18, and extends beyond the end of head 11 into the bristles 13, said closed end being provided 85 with an eccentric opening 19.

Mounted for slidable movement in the bore 7 of the handle 6 is a piston 21 which is provided with a central threaded aperture 22 for threaded engagement with a screw threaded rod 23 wherein said rod extends longitudinally throughout the length of said bore. Diametrically opposed lugs 25 extend radially from the piston 21 and are received in the grooves 8 for slidable movement therein, and function to prevent the said piston from rotating in said bore when the screw 23 is rotated. Means are provided for rotating said screw in the bore 7, thereby causing the piston 21 to move to 100

wards or away from the head 11, depending on the direction of rotation of the screw 23. Said means comprises a cap 24 having a socket 26 for receiving the end of the cylinder handle 6, opposite to the brush end of said handle, and to which cap the screw 23 is secured, so as to rotate therewith, as at 27. In order that the cap 24 may be rotatably and removably secured to the handle 6, the said handle is provided with a projection or pin 28 which extends radially from the outer surface of the handle adjacent the end thereof. Said pin is slidably received in an annular groove 29 formed in the wall 15 of the socket 26. A vertical groove 31 extends from the edge of the bore 26 to the annular groove 29, and in this manner when it is desired to remove the cap 24 from the handle 6 it is merely necessary to turn said cap until the projection 28 is in alignment with the vertical groove 31, at which time a pull exerted on the said cap causes the pin to slide through the groove 31 allowing the removal of said cap from said handle.

25 It will now be seen that when the bore 7 of the handle 6 is filled with a paste, such as a shaving cream, and the screw 26 is rotated by means of the cap 24 so as to cause the piston 23 to move toward the head 11, 30 the contents of the said handle will be forced through the sleeve 16 and discharged from the aperture 19 into the bristles 13. By dipping the bristles 13 in warm water the brush 5 is ready to be used for lathering the 35 face.

In order that only a predetermined quantity of shaving cream, sufficient to lather the face, be discharged from the handle 6 when the cap 24 is rotated, means, operable 40 by said cap, are provided in the head 11 for governing the discharge of shaving cream through the opening 19. Said means comprises a valve disc 32 which is fitted into the sleeve 16 and rests upon the base 45 18 thereof, as is clearly shown in Fig. 2. A socket 33 is formed in the center of the disc 32 for removably receiving the free end of the screw rod 23, and wherein the end of said rod and said socket are provided 50 with means for preventing relative rotation, which means may consist of radially extending pins on the end of said rod, which pins engage in slots which extend radially from said socket. The disc 32 is provided 55 with a quarter circular concentric slot 34 which aligns with the opening 19 in the base 18 of the sleeve 16, when turned so as to be in registry therewith.

In operation, the brush may be held in 60 one hand and the cap 24 turned by the other hand, in a clockwise direction, which turning rotates the screw rod 23 and causes the piston 21 to move towards the head 11. Rotation of the screw rod 23 also rotates the 65 disc valve 32, which rotation brings the slot

34 in registry with the opening 19 and allows the shaving cream compressed by the downward movement of the piston 21 to discharge through said slot and said opening into the bristles 13. Continued rotation of the screw 23 causes the slot 34 to be turned past the opening 19 thereby shutting off the discharge of shaving cream. In this manner sufficient shaving cream will be discharged into the brush 13 by one complete turn of the cap 24 to lather the face. However, if it is desired to discharge more of the shaving cream into the brush, it is merely necessary to turn the handle 24 another complete turn.

70 Removal of the plunger 21 from the bore 7 of the handle 6 for refilling said handle with shaving cream is accomplished by turning the cap 24 until the pin 28 is in alignment with the slot 31, whereupon the said cap is pulled outwardly, which movement draws the rod 23 and the piston 21 out of the bore 7.

75 In this specification, and the annexed drawings, the invitation is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

80 I claim:

1. A dispensing device of the character 100 described comprising a handle having a central longitudinal bore and an aperture formed in and extending through one end of said handle and communicating with said bore, a piston movable axially in said bore, a screw axially mounted in said bore and extending through said piston in threaded engagement therewith, whereby rotation of said screw moves said piston for discharging the contents of said handle through said aperture, a brush part attached to the end of said handle for receiving the discharge from said handle, a disc mounted so as to cover said aperture and concentrically mounted relative thereto, said disc being 105 connected to the end of said screw so as to rotate therewith and being provided with an eccentrically disposed aperture for registering with said first aperture, whereby rotation of said screw moves said apertures 110 into and out of registry.

115 2. A dispensing device of the character described comprising a handle having a central longitudinal bore, a sleeve axially mounted in the end of said handle so as to communicate with the interior thereof, the outer end of said sleeve being closed and provided with an eccentrically disposed aperture, a piston movable axially in said bore, a screw axially mounted in said bore 120 125 130

and extending through said piston in threaded engagement therewith, whereby rotation of said screw moves said piston for discharging the contents of said handle through said aperture, a brush part attached to the end of said handle for receiving the discharge from said handle, a disc carried by said sleeve so as to cover said aperture, said disc being connected to the inner end of said screw so as to rotate therewith and being provided with an eccentrically disposed aperture for registering with said first aperture, whereby rotation of said screw moves said apertures into and out of registry.

3. A dispensing device of the character described comprising a handle having a central longitudinal bore, a head removably attached to one end of said handle, a sleeve secured in a central aperture in said head and extending beyond the outer end thereof, the outer end of said sleeve being closed and provided with an eccentrically disposed aperture, a piston movable in said bore and provided with radially extending lugs for engagement in longitudinal grooves formed in said bore, a screw extending axially through said piston in threaded engagement therewith, a cap having a socket adapted to fit over the other end of said handle, a pin extending radially from the end of said handle and receivable in an annular groove in said socket through a vertical groove extending from said annular groove to the edge of said cap, said screw being secured at its outer end to said cap so as to be rotated thereby, whereby rotation of said cap moves said piston for discharging the contents of said handle through said aperture, a brush part set in the outer end of said head for receiving the discharge from said handle, a disc carried by said sleeve so as to cover said aperture, said disc being connected to the inner end of said screw so as to rotate therewith and being provided with an eccentrically disposed aperture for registering with said first aperture, whereby rotation of said screw moves said apertures into and out of registry.

50 In testimony whereof I have affixed my signature.

LUTHER W. WAKEHAM.
